UNITED STATES PATENT OFFICE.

ALEXANDER GORDON, OF NEW YORK, N. Y.

IMPROVEMENT IN REGISTERING MARINE LOGS.

Specification forming part of Letters Patent No. 40,834, dated December 8, 1863.

To all whom it may concern:

Be it known that I, ALEXANDER GORDON, of the city, county, and State of New York, have invented a new and useful Improvement in the Registering Marine Log; and I do hereby declare that the following is a full, clear, and exact description of the same, reference being had to the accompanying drawings, forming part of this specification, in which—

Figure 1 is a vertical section of a log with my improvement. Fig. 2 is a plan of the compass.

Similar letters of reference indicate corresponding parts in both figures.

The object of this invention is to register the directions of the distances run by a ship or other vessel as well as the distances themselves; and to this end it consists in the combination, with an apparatus substantially like what has been heretofore known as the "registering marine log," or "patent log," of a compass of peculiar construction, and an apparatus connected with the registering mechanism for dropping pellets into a compartment of the said compass whenever a certain distance has been made by the vessel to which the log is applied.

To enable others skilled in the art to make and use my invention, I will proceed to describe it.

A is a hollow upright shaft extending from the cabin down through the bottom of the vessel, and having securely and rigidly attached to its lower end a vane, B, which by the equal pressure of the water on opposite sides of it is always kept in a plane parallel with the direction of the vessel through the water. Besides the vane B there is also rigidly secured to the lower part of the shaft A, under the bottom of the vessel, a box, C, which contains the bearings of the horizontal shaft *a*, to which is attached the small screw-propeller-like wheel D, which has rotary motion given to it by the pressure of the water as it is carried through it by the vessel. The vane B always remains behind the shaft and the propeller in front of it. The shaft *a* has upon its periphery a screw-thread which gears with a worm-gear, (not shown,) which is fast on the lower end of a shaft, *b*, which passes directly through the hollow shaft A up into the cabin, and on the upper part of which there is a screw-thread, *c*,

which gears with a worm-gear, *d*, on the first shaft, *d'*, of the registering-train *d e f g*, which is furnished with indices *h i j*, to indicate upon suitable dials the number of knots or miles run by the vessel. The apparatus which I have thus far described does not differ essentially in construction or operation from some of the self-registering logs heretofore used. The propeller D and screw-thread on its shaft *a* give motion to the gear at the bottom of the shaft *b* and to the said shaft, and the screw-thread *c* gives motion to the worm-gear *d* and to the registering-train.

E is compass-box suspended within the cabin from any suitable support, F, by means of a jointed frame, G G H I S, the pendulous side pieces, G G, of which are hung on gimbals *m m*, so that the compass-box is always in a horizontal position. The center piece, H, of this frame, which is rigidly attached to the box E, and concentric and perpendicular thereto, is connected by cross-pieces I and pin-joints *k k l* with the pendulous side pieces, G G, and it is made of tubular form to permit the passage through it of a tube, J, which is also suspended from the support F by means of a gimbal, *n*. The lower part of this tube is bent outward from the center of the compass-box and compass, and the upper part is connected by a flexible tube, *p*, with the guard or shell *q*, which partly surrounds a vertical wheel, K, the upper part of which works in the throat of a hopper, L, containing a number of shot or pellets, *r r*. This wheel K has in its periphery, at equal distances apart in a circumferential line, a row of cup-like cavities, *s s*, which are just large and deep enough to receive each one of the shots or pellets *r r* from the hopper as the said cavities pass through the throat of the hopper in the revolution of the wheel. The wheel is geared with a pinion, *t*, on a shaft, *u*, which has also secured upon it a ratchet-wheel, *u'*, in which works a pawl, *v*, connected with an eccentric, *v'*, on the first shaft, *d'*, of the register-train. The gimbal *n*, in which the tube J is hung, is supported in a horizontal spur-gear, M, which works in a suitable bearing in the support F, and which corresponds in size and number of teeth with a spur-gear, N, on the hollow shaft A, to which the vane B is secured, and the two gears M N are geared together by

an intermediate gear, P, so that the tube J is compelled to turn with and in the same direction as the hollow shaft A, when the latter is turned by the action of the water on the vane B, on any change in the direction of the vessel. The gears M N P are so geared that the bent lower end of the tube J will always point in the opposite direction to the vane B, and consequently in the direction in which the vessel is moving through the water.

The compass-card Q is attached to the top of a light box, R, of card-board or other light material, in which there are a number of radial partitions, $\alpha\alpha$, forming a number of equal radial compartments, $z z$, corresponding with the principal divisions of the compass—either sixteen or thirty-two—the said compartments having openings which present themselves opposite the opening in the lower end of the tube J. The card Q and box R are attached to the magnetic needle, and the whole balanced in the usual way on a central point, y, secured in the box E. The compartments may each have a cup, z' , in the bottom for the reception of the pellets, which are dropped into them from the tube J.

As the registering apparatus operates the eccentric v' actuates the pawl v and produces an intermittent rotary movement of the ratchet-wheel u' , gear t , and wheel k , such movement taking place at the completion of each mile or other distance run by the vessel, and being sufficient to present a new cavity s opposite

to the lower opening of the casing q , where the pipe p is connected, and hence as the cavities $s s$, which are between the hopper and the pipe p , each contain a pellet, the said movement causes a pellet to be deposited in the pipe p , down which and down the pipe J it passes, and from the latter of which it drops into such one of the compartments $z z$ of the compass as the mouth of the tube J may be over, according to the direction of the vessel. By counting the pellets which have at any time been received in the compartments the distance run by the vessel toward each point of the compass is ascertained. The whole distance run is ascertained by the indices $h i j$.

What I claim as my invention, and desire to secure by Letters Patent, is—

The combination, with the registering marine log, of a compass divided into compartments $z z$ for the reception of pellets or their equivalents, and an apparatus for dropping a pellet into one of said compartments whenever the vessel has made a certain distance, the delivering tube or portion of the said dropping apparatus being so controlled as to always point in the direction in which the vessel is moving through the water, and the whole operating substantially as and for the purpose herein specified.

ALEXANDER GORDON.
